UNITED STATES PATENT OFFICE

157,909

COMPACT OR THE LIKE

Jean Schlumberger, New York, N. Y.

Application June 3, 1949, Serial No. 3,028

Term of patent 7 years

(Cl. D86—10)

To all whom it may concern:

Be it known that I, Jean Schlumberger, a citizen of France, residing in New York city, county of New York, and State of New York, have invented a new, original, and ornamental Design for a Compact or the like, of which the following is a specification, reference being had to the accompanying drawing, forming part thereof, wherein,

I claim:

The ornamental design for a compact or the like, substantially as shown.

JEAN SCHLUMBERGER.
